205,500

HOLDER FOR A DISPOSABLE MOP

Marsha Deitel and Norman Deitel, both of 67 Stoneham Place, Metuchen, N.J.

Filed Sept. 24, 1965, Ser. No. 87,154

Term of patent 14 years

(Cl. D9—2)

FIG.1

FIG. 5

FIG. 1 is a top plan view of a holder for a disposable mop, showing our new design.

FIG. 2 is a side elevational view thereof.

FIG. 3 is a bottom plan view thereof.

FIG. 4 is an elevational view thereof taken from the right of FIG. 1, the opposite end taken from the left being a mirror image thereof.

FIG. 5 is a perspective view thereof, showing the holder in partial operating position.

The broken lines shown in FIGS. 1-5 are for illustrative purposes only.

We claim:

The ornamental design for a holder for a disposable mop, as shown and described.
